UNITED STATES PATENT OFFICE.

JAMES FLOWER, OF DETROIT, MICHIGAN.

SIZING-TOOL FOR LATHES.

SPECIFICATION forming part of Letters Patent No. 259,377, dated June 13, 1882.

Application filed February 21, 1882. (No model.)

To all whom it may concern:

Be it known that I, JAMES FLOWER, of Detroit, county of Wayne, State of Michigan, have invented a new and useful Improvement in Sizing-Tools for Lathes; and I declare the following to be a full, clear, and exact description of the same, reference being had to the accompanying drawings, which form a part of this specification, and wherein—

10 Figure 1 is a perspective view of my sizing-tool. Fig. 2 is a horizontal central section thereof. Fig. 3 is a cross-section of one of the cutting-tools, showing the manner of fastening it to the tool-holder or face-plate. Fig. 4 is a diagram showing the relative positions of cutting-tools and steadyng-supports.

In a patent granted to me December 6, 1881, and numbered 250,514, I have described a turret-lathe provided with a monitor-head "capable 20 of holding a multiplicity of tools, so that in turning the metal castings the thread is cut or the casting trimmed without removing the tool from its socket."

The object of my invention is to provide a 25 tool for said monitor-head, especially adapted for sizing castings, and doing it in a very expeditious and always uniform manner, allowing at the same time a simple and quick adjustment of the cutting-tools.

30 In the drawings, A is a face-plate provided with the central orifice, B.

C is a support, to which, at one end, the face-plate is attached in any convenient manner, while the other end terminates into a shank, 35 D, for securing the tool into the lathe-head.

E E are cutting-tools sunk into proper recesses of the face-plate and upon opposite sides thereof, with their cutting-edges extending within the orifice B. They are held in place 40 by the wedge-headed bolts F F, which pass through the face-plate A, and are provided on the rear side thereof with the nuts a. The side of the cutting-tools which comes in contact with the wedge-shaped heads of the bolts is similarly shaped, so as to allow the bolts to hold 45 the cutting-tools very firmly.

G are steadyng pins or posts sunk into the face-plate at right angles to the cutting-tools, one above and one below the center. They 50 are adjustably secured within their recesses,

in the same manner as the cutting-tools, by similar bolts, H H.

The cutting-tools E E are not arranged radially upon the face-plate A, but are parallel to each other, one above and the other below a 55 horizontal plane passing through the axial center of the tool-holder, and as their cutting-edges are presented in opposite direction they are thus enabled to work simultaneously upon the revolving and advancing casting. 60

In practice the casting to be sized is revolved by the live-spindle, and the tool being advanced with the lathe-head the two cutting-tools E E can very rapidly size the casting, as they both 65 cut at the same time, and as they also work in the same vertical plane and upon opposite sides they tend to steady the work.

For relatively long or slender castings, where there may be danger of bending or springing the same, I use the steadyng-posts G G in 70 combination with the cutting-tools. Fig. 4 shows in a diagram the action of the steadyng-posts, whose inner ends are shown to steady the casting at the sized part, and as near to the unsized as possible, so as to come into action 75 as soon as the cutting-tools begin to work.

The support C may be made in the form of a yoke, or, as shown in the drawings, in form of a hollow tube, which gives to the tool the requisite stiffness, if the same has to be made 80 comparatively long, to allow the sized portion of the casting to enter. Proper holes have then to be provided to let the turnings fall out.

Although I get the full benefit of my tool by using it in a monitor lathe-head, I do not intend to confine myself to such use only, as the tool may be used with equal benefit on any lathe provided with a lathe-head adapted to be advanced and retracted.

I am aware that screw-cutting tools have 90 been supplied with cutting and steadyng attachments secured to a rotating head, and I do not claim such invention.

What I claim is—

1. The support C, provided with a face-plate, 95 A, having recesses, two of which are radial to the center, and the other two, one above and the other below said center, in combination with tools having cutting-edges on opposite sides to each other, and steadyng-posts hav- 100

ing smooth bearing-surfaces, both the cutters and the steadyng-posts being firmly secured in the recesses in the face-plate, with the working-edges of the cutters in advance of the bearing-surfaces of the steadyng-posts, substantially as and for the purpose specified.

2. The support C, having openings to allow of the escape of the turnings, in combination with the recessed face-plate A, cutters E, secured to said face-plate, and the steadyng-posts G, also secured to the face-plate, and having their bearing-surfaces at the rear of the cutting-edges of the cutters E, substantially as and for the purpose specified.

15 3. The support C, provided with a face-plate,

A, having recesses to receive the tools E G, and having a hole with one inclined side opening into each of the recesses, in combination with the tools E G, having an inclined side adjoining the holes in the face-plate, the sliding bolts F, having inclined sides to come in contact with the inclined sides of the tools and the holes adjoining the tool-recesses, and the nuts a, for operating said sliding bolts, substantially as and for the purpose specified. 20

JAMES FLOWER.
